UNITED STATES PATENT OFFICE.

JAMES HARLEY NASH, OF CALDWELL, NEW JERSEY, ASSIGNOR TO LEE NASH DISPLAYS, INCORPORATED, OF NEW YORK, N. Y., A CORPORATION OF NEW YORK.

DESIGN FOR AN ADVERTISING DISPLAY STAND.

Application filed May 1, 1926. Serial No. 17,532. Term of patent 3½ years.

To all whom it may concern:

Be it known that I, JAMES HARLEY NASH, a citizen of the United States, residing in Caldwell, county of Essex and State of New Jersey, have invented a new, original and ornamental Design for Advertising Display Stands, of which the following is a specification, reference being had to the accompanying drawing, forming a part thereof.

Figure 1 is a front perspective view of the display stand showing my new design; and

Figure 2 is a side perspective view thereof.

What I claim is:

The ornamental design for an advertising display stand substantially as shown.

JAMES HARLEY NASH.
